UNITED STATES PATENT OFFICE.

M. G. HUBBARD, OF SYRACUSE, NEW YORK.

IMPROVEMENT IN MOWING-MACHINES.

Specification forming part of Letters Patent No. 44,629, dated October 11, 1864.

To all whom it may concern:

Be it known that I, MOSES G. HUBBARD, of the city of Syracuse, in the State of New York, have invented certain new and useful Improvements in Mowing-Machines; and I do hereby declare the following to be a full and clear description thereof, reference being had to the accompanying drawings, in which—

Figure 1 is a top view of the inner end and "head" of the cutter-bar which forms the subject of my present improvement. Fig. 2 is an end view thereof, and Fig. 3 is a front view of the same.

In Fig. 1, A is a malleable iron head, like those in common use on the Kirby and several other mowers, and is riveted on the inner end of the cutter-bar in order to form a jaw for the connection of the pitman thereto, and in order to give broad surfaces by which to hold the inner end of the cutter-bar in place.

B is the cutter-bar, and, as shown in Fig. 3, C is a piece on the under side to stiffen and strengthen the inner end of the cutter-bar.

D is the point where the bar forming the cutter-bar is bent around under, and the short under piece is thus absolutely connected to the cutter-bar much more securely than could possibly be done by the rivets alone, and in such a manner as to effectually resist endwise vibrations, and thus avoid the crystallization of the parts and their consequent breakage, because this connection of the two parts of the bar is almost equivalent to a solid bar of double thickness at the inner end, and this increased thickness, having such endwise strength and absolute endwise connection, gives greater stability to the rivets and the attachment of the cutter-bar head thereby.

The object of my present improvement is to provide a remedy for the general liability of the cutting-bars to break at the inner end while at work. The liability of these bars to break has come to be one of the most serious obstacles in the way of a general introduction of mowing-machines, and has no doubt caused farmers more trouble, delay, loss, and expense than all the other sources of trouble together experienced in the use of modern mowing-machines.

After an extended series of experiments I have found that by bending and doubling under about one foot of the inner end of the steel bar forming the cutter-bar, so as to make the inner end double and actually connected at the end, the short under piece is so connected to the upper piece as absolutely to prevent the possibility of endwise vibration, and in that respect almost equal to a solid bar of double thickness. By this sort of union between the upper bar and the lower piece most of the strain which the rivets in holding these two pieces together would get in actual work is sustained by the end connection, and this connection adds greatly to the strength of the combined parts in every respect.

Having thus fully described my improvement in mowing-machines, what I claim as new therein, and desire to secure by Letters Patent, is—

The manner of constructing and strengthening the cutter-bar, substantially as and for the purposes set forth.

M. G. HUBBARD.
